UNITED STATES PATENT OFFICE.

BLANCHE STEVENS ARVOY, NÉE RENEAUX, OF PARIS, FRANCE, AND CHARLES LIONEL MARCUS, OF NEW YORK, N. Y.

DESIGN FOR A COMBINED STAND AND HOLDER FOR PERFUME BOTTLES.

Application filed December 12, 1924. Serial No. 11,687. Term of patent 3½ years.

To all whom it may concern:

Be it known that BLANCHE STEVENS ARVOY, née RENEAUX, citizen of the Republic of France, and residing in Paris, France, and CHARLES LIONEL MARCUS, citizen of the United States, and resident of the city of New York, in the county of New York and State of New York, have invented a new, original, and ornamental Design for Combined Stand and Holder for Perfume Bottles, of which the following is a specification, reference being had to the accompanying drawing, forming part thereof, in which—

Fig. 1 is a top plan view of a combined stand and holder for perfume bottles embodying our new design;

Fig. 2 is a front elevational view thereof; and

Fig. 3 is a side elevational view thereof showing a portion cut away to expose the ornamentation on the interior side panels.

We claim:

The ornamental design for a combined stand and holder for perfume bottles, as shown and described.

Signed at Paris, France, November 10, 1924.

BLANCHE STEVENS ARVOY, née RENEAUX.

Signed at New York city, October 28, 1924.

CHARLES LIONEL MARCUS.
